(57) **CLAIM**

The ornamental design for a portion of a display screen with a changeable graphical user interface component, as shown and described.

DESCRIPTION

FIG. 1 is a front view of a portion of a display screen with a changeable graphical user interface component showing a first image in a sequence according to a first embodiment; FIG. 2 is a front view of a second image included in the sequence of the first embodiment; FIG. 3 is a front view of a third image included in the sequence of the first embodiment; FIG. 4 is a front view of a portion of a display screen with a changeable graphical user interface component showing a first image in a sequence of a second embodiment; FIG. 5 is a front view of a second image included in the sequence of the second embodiment; FIG. 6 is a front view of a third image included in the sequence of the second embodiment; FIG. 7 is a front view of a portion of a display screen with a changeable graphical user interface component showing a first image in a sequence of a third embodiment; FIG. 8 is a front view of a second image included in the sequence of the third embodiment; FIG. 9 is a front view of a third image included in the sequence of the third embodiment; FIG. 10 is a front view of a portion of a display screen with a changeable graphical user interface component showing a first image in a sequence of a fourth embodiment; FIG. 11 is a front view of a second image included in the sequence of the fourth embodiment; FIG. 12 is a front view of a third image included in the sequence of the fourth embodiment; FIG. 13 is a front view of a portion of a display screen with a changeable graphical user interface component showing a first image in a sequence of a fifth embodiment; FIG. 14 is a front view of a second image included in the sequence of the fifth embodiment;

(Continued)

FIG. 15 is a front view of a third image included in the sequence of the fifth embodiment;

FIG. 16 is a front view of a portion of a display screen with a changeable graphical user interface component showing a first image in a sequence of a sixth embodiment;

FIG. 17 is a front view of a second image included in the sequence of the sixth embodiment; and,

FIG. 18 is a front view of a third image included in the sequence of the sixth embodiment.

The longer-incremented broken lines showing of a portion of a display screen of a communications terminal illustrate environment and form no part of the claimed design. The outer medium length broken line shows the bounds of the claimed design and forms no part thereof. The finer-incremented broken line showing an icon and text is included for the purpose of illustrating portions of the graphical user interface and forms no part of the claimed design.

The gray shading and stippling in the drawings indicate a contrast of appearance.

The subject matter in this patent includes a process or period in which an image changes into another image. The process or period in which an image transitions to another image forms no part of the claimed design.
